AUTOMOBILE ROOF TOP DISPLAY SIGN OR SIMILAR ARTICLE

Harry E. Bissell, Murrysville, Pa., assignor to
IDL Inc., Pittsburgh, Pa.

Filed Apr. 29, 1975, Ser. No. 572,904

Term of patent 14 years

Int. Cl. D20—03

U.S. Cl. D96—12 R

Fig. 1

Fig. 2

FIG. 1 is a perspective view of an automobile roof top display sign or similar article showing my new design; the automobile is shown in broken lines for illustrative purposes only, and

FIG. 2 is a perspective view thereof on an enlarged scale.

I claim:

The ornamental design for an automobile roof top display sign or similar article, as shown and described.
